UNITED STATES PATENT OFFICE.

JOHN J. CAIN, OF BAYONNE, NEW JERSEY.

OIL HEATING SYSTEM FOR LOCOMOTIVE BOILERS.

Application filed September 9, 1922. Serial No. 587,249.

To all whom it may concern:

Be it known that I, JOHN J. CAIN, a citizen of the United States, and a resident of Bayonne, county of Hudson, State of New Jersey, have invented new and useful Improvements in Oil Heating Systems for Locomotive Boilers, of which the following is a specification.

The oil burner of this invention is designed to heat boilers of considerable length, such as locomotive boilers which are now constructed with the fire at one end only. Under the existing method of operating boilers the fire at one end of the boiler has to be maintained at a very high temperature to produce effective heating at the other parts as the products of combustion pass and act on the heating surfaces the full length of the boiler, which naturally results in unequal heating, of considerable variance, of the different parts of the boiler. The damaging effects of the very high temperature maintained in the furnace is also a matter of considerable importance.

To correct this deleterious feature in heating long boilers this invention provides auxiliary furnaces located under the boiler, ahead of the rear end furnace, at parts that are acted upon by the reduced heat of the partly spent gases thereof; the heat of the auxiliary furnaces acts with and augments the reduced heat of the products of combustion from the end furnace and so causes all parts of the boiler to be uniformly heated.

The type of boilers to which my present improvements in oil burners is particularly applicable is shown in my U. S. Letters Patent No. 1,463,250, issued July 31, 1923, in which the water holding and heating elements consist of narrow hollow sections transversely arranged and of a size to substantially occupy the whole of the transverse area of the available space for the boiler above the running gear of the locomotive, and walls or baffles, alternately arranged, extending from the bottom of the boiler to the under edge of a section and extending downwardly from the top of the boiler to the upper edge of another section, thereby longitudinally dividing the boiler into sections or divisions through which the products of combustion are alternately directed upwardly and downwardly from the furnace at one end of the boiler to the exit opening at its other end.

The invention contemplates the employment of an auxiliary or secondary furnace,

as an oil burner when oil is used as the heating means of the boiler, at a longitudinal division ahead of the main furnace to augment the heat applied to the sections of the forward divisions, thereby greatly increasing the steaming qualities of the boiler; in other words the invention may be considered as a heat equalizer, whereby an uniformity of heat will be applied to all of the sections of the boiler, thus avoiding strains from unequal heating; it being also understood that by reason of this heat equalizing system the end or main fire may be so reduced in intensity as to avoid damage due to excessive heating of the crown sheets and side walls of the furnaces of ordinary boilers or of the transverse sections in or constituting the main fire chamber of this boiler.

In applying this heat equalizing method to locomotive boilers a chamber or chambers, the equivalent of a fire box or fire boxes, will be formed at the part or parts selected to receive the additional heat, in which the auxiliary oil burners will be located, and said fire boxes will be provided with openings and dampers adapted to be closed when the auxiliary furnaces are out of action; the arrangement being such that the burners and their accompanying air dampers may be controlled from the cab or firing end of the boiler, thus enabling the engineer to run the boiler on the main fire only, when such provides the necessary heat, or to put into action the auxiliary fire or fires as the steaming requirements demand.

In the accompanying drawings an embodiment of devices suitable for the purposes of this invention are illustrated, in which:

Fig. 1, is a longitudinal section of a locomotive boiler provided with the improved heating means of this invention.

Fig. 2, is a transverse section of the main fire box of the boiler, taken on the line 2, 2, Fig. 1, and

Fig. 3, is an enlarged view of an auxiliary burner and its air damper.

The narrow hollow sections 4, 4, of the boiler, the steam equalizing drum 5, located at the central upper parts of the sections and connected by nipples thereto, are as shown in my before-mentioned patent. Other parts of the boiler, as the longitudinal mud chambers 6, connected to the bottoms of the side legs of the sections 4, the upper baffle wall 7, lower baffle wall 8, which divide the boiler

into longitudinal sections or divisions, the main fire box 9, smoke chamber 10, the super-heater sections 11, connected between the dry pipe 12 and the steam pipe 13, and the cab 14, are in all essential respects similar to the corresponding parts of my application No. 565,348, filed June 2, 1922.

The main oil burner 15, which may be of any suitable kind, as for instance a steam spray burner, is located at the rear end of the boiler to direct its flame through the fire box 9 towards the furnace back wall 16. The products of combustion after ascending around the first set of sections 4, pass downwardly around the second set, being directed thereto by the upper baffle wall 7, thence upwardly through the third set of sections, directed by the lower baffle wall 8, and finally downwardly through the last set of sections to the opening of the smoke chamber 10.

The invention is not necessarily limited to sectional boilers, as shown, nor to the number of up and down draft divisions shown, which in very long boilers be increased to any desired or adequate extent, but in long boilers the fall in temperature of the furnace gases from the firing end to the exit end is considerable, and to raise effective steam throughout the boiler, by the end fire only, intense heat must be maintained at the furnace end, often of a damaging character to this part of the boiler.

Now the method of heating boilers involved in this invention avoids the necessity of intensely heating the furnace end; it produces the maximum quantity of steam at maximum pressure within the capacity and strength of the boiler without dangerously heating any part thereof. This is accomplished by the use of an auxiliary oil burner 17, arranged to direct its flame into a fire box 18, located beneath the third division of the transverse sections 4, said fire box having an opening provided with a closing door or damper 19.

It is evident that ordinarily the hot gases from the end furnace 9 will have fallen considerably in temperature by the time they enter the forward fire box 17, where they commingle with the hot gases of the burner in said fire box; the temperature of the mixed gases then heating the forward part of the boiler substantially equal to the heating effects at the rear end of the boiler of the fuel combustion in the end furnace 9. This result is assisted or expedited by the retarding effects of the construction of the type of boiler shown, which divides the area of the up draft outlet from the fire box 17, into a number of narrow transverse passages formed by the spacing apart of the boiler sections 4, and so causing the hot mixed gases to be uniformly distributed among the sections.

Means are provided for operating the oil

burner 17 from the cab 14, so that it is always under the control of the engineer to be manipulated to meet the hauling requirements of the engine, comprising a shaft 20, rocking in a bracket bearing, and having on its inner end an arm connected by a link 21 to the stem of the valve 17, and by link 22 to the damper door 19. The other end of the shaft 20, located beneath the side of the boiler, has an arm 23, to which is attached a rod 24, extending rearwardly to the cab and there connected to an operating lever 25. The outer end of the shaft is held in a bearing 26.

By this arrangement the damper may be set to regulate the air supplied to the burner and be closed when the burner is shut off.

It may in some cases be desirable to employ another burner 27 to supply additional fire in the fire box 9; this burner and its air supply may be controlled by means similar to that applied to the burner 17, comprising a controlling hand lever 28, in the cab; a rod 29 connecting this lever to an arm 30 of the shaft 31, having a bearing in a bracket, a link connection 32 between the arm 30 and the stem 33 of the burner valve and a link 34 connecting the arm to the damper door 35 of the air opening.

36 and 37 designate pilot burners for the oil burners 17 and 27 respectively.

The transverse sections 4 are here shown as having plain flat sides; the corrugated sections of my before-mentioned application may be used in this case.

I claim:

1. An oil heating apparatus for locomotive boilers, comprising a main oil burner in a fire box at the rear end of the boiler, transverse baffle walls dividing the boiler into alternate up and down draft passages, an auxiliary fire box at the lower end of and opening into an up draft division ahead of the end fire box and oil burning means in said auxiliary fire box, whereby the high temperature gases of combustion of the auxiliary burner mix with the partly heat spent gases from the burner at the rear end of the boiler and thereby insures in all parts of the boiler practically uniform steaming results.

2. An oil heating apparatus for locomotive boilers, comprising a main oil burner in a fire box at the rear end of the locomotive, a separate independent open top fire box intermediate the end fire box and the smoke exit at the other end of the boiler and an oil burner in said intermediate fire box and over which the partly heat spent gases from the end furnace pass and mix with the hot gases from the auxiliary burner whereby the boiler throughout its length is substantially uniformly heated.

3. The method of heating a long boiler having a heating means at one of its ends,

the gaseous products of combustion acting on the boiler throughout its length to its other end, or forward part which consists in applying the initial heat of a burning fuel 5 to the boiler intermediate its ends to commingle with the partly heat spent gases from the end fire and with them act on the forward part of the boiler.

4. A locomotive boiler, comprising narrow 10 hollow sections transversely arranged and spaced apart to afford vertical heating passages between them, combustion spaces at the under edges of the sections and a passage along the tops of the sections into which 15 all of the vertical passages open, a fire box and heating means therein at the rear end of the boiler, a baffle wall closing the combus-

tion space at the under edge of a section at the front end of the rear end fire box, a baffle wall athwart the top passage and resting on the top of another section in advance 20 of the said lower baffle wall, an independent fire box located under and opening into a division of the sections ahead of the upper baffle wall, an auxiliary burner in said independent fire box, a baffle wall closing the combustion space at the under edge of a section at the front end of the forward fire box and a flue exit from the combustion spaces 25 of the last division of sections ahead of the last mentioned baffle wall.

Signed at New York, county and State of New York, this 6th day of September, 1922.

JOHN J. CAIN.
